DESIGN FOR FABRIC FOR CLOAKING, &c.

UNITED STATES PATENT OFFICE.

HENRY TOPHAM, OF PHILADELPHIA, PENNSYLVANIA, ASSIGNOR TO
SCHEPPERS BROTHERS, OF SAME PLACE.

DESIGN FOR FABRIC FOR CLOAKING, &c.

SPECIFICATION forming part of Design No. 19,084, dated May 7, 1889.

Application filed March 28, 1889. Serial No. 305,493. Term of patent 3½ years.

To all whom it may concern:

Be it known that I, HENRY TOPHAM, a citizen of the United States, residing at the city of Philadelphia, in the county of Philadelphia and State of Pennsylvania, have invented and produced a new and original Design for Fabric for Cloaking, &c., of which the following is a specification, reference being had to the accompanying photograph, forming part 10 of hereof, illustrating in front elevation the design embodying the characteristic features of my invention.

The leading feature of this design consists of fanciful configurations forming stripes disposed lengthwise through the goods, and these configurations formed of dots, dashes, and full lines arranged parallel, or substantially so, to each other, as hereinafter more particularly described.

20 In the accompanying photograph, A represents one of the stripes embodying the several characteristic features of the design repeated throughout the length of the goods. The configuration constituting the design is made of dots, dashes, or full lines disposed parallel, or substantially so, to each other in the configurations. Starting from the top of the design, it consists of an oval-shaped fanciful figure (designated by the letter B) with pointed 25 end portions. This oval-shaped figure is made up of numerous dots, dashes, or full lines dis-

posed parallel, or substantially so, to each other, and forming bars c, with spaces d between each of them. In the center of this oval-shaped fanciful figure B is a conventional four-leaf clover, C. Between the upper and lower terminal portions of the oval-shaped figures are inversely-arranged arrow-heads D and D', made up of dots, dashes, or full lines, and in the field adjacent to the respective arrow-heads 35 40 is arranged a horizontal bar, E, formed of a series of vertical parallel lines with spaces between them, but forming fanciful marks.

The above-described fanciful configurations constituting the stripes of the design are repeated throughout the goods, in the manner 45 illustrated, for instance, in the accompanying photograph.

Having thus described the nature and objects of my invention, what I claim as new, and 50 desire to secure by Letters Patent, is—

The design for fabric for cloaking, &c., as herein described, and shown in the accompanying illustration.

55 In witness whereof I have hereunto set my signature in the presence of two subscribing witnesses.

HENRY TOPHAM.

Witnesses:

HERMANN BORMANN,
THOMAS M. SMITH.
